AUXILIARY AIR CONTROL FOR INTERNAL COMBUSTION ENGINES

Filed July 21, 1925

Patented Feb. 16, 1926.

1,573,692

UNITED STATES PATENT OFFICE.

ELMER A. EKLUND, OF SPENCER, SOUTH DAKOTA.

AUXILIARY AIR CONTROL FOR INTERNAL-COMBUSTION ENGINES.

Application filed July 21, 1925. Serial No. 45,115.

To all whom it may concern:

Be it known that I, ELMER A. EKLUND, a citizen of the United States, residing at Spencer, in the county of McCook and State 5 of South Dakota, have invented certain new and useful Improvements in Auxiliary Air Controls for Internal-Combustion Engines, of which the following is a specification, reference being had to the accompanying drawings.

This invention relates to devices for admitting air to the manifold of an internal combustion engine to thereby save fuel and secure a better operation of the engine, and particularly to devices of this character 15 wherein the air is drawn into the manifold upon each pulsation of the engine and wherein means are provided for controlling the amount of auxiliary air thus passing 20 into the manifold.

The general object of the invention is to provide a device of this character which is very simple, which has been found extremely effective in practice, and which may be 25 cheaply made and readily attached to all makes of automobiles.

A further object is to provide a device of this character which is controlled by means 30 on the dashboard of the machine.

A still further object is to provide a device of this character including an air inlet pipe connected by tubing to the manifold between the carburetor and the inlet of the manifold to the cylinders of the engine, and 35 provide in said inlet pipe a spring-pressed ball valve normally held to its seat by the effect of the spring but withdrawn from the seat by the suction of the engine, the valve being of spherical shape so as to permit the 40 air to readily pass around the valve and pass down through the tubing.

Another object is to provide a cut-off valve controlling the inlet of air to the air inlet pipe and which may be readily adjusted to 45 vary the amount of air so drawn into the engine.

Still another object is to provide a device of this character wherein the ball is properly seated and wherein the spring is not allowed 50 to touch the barrel or inlet pipe within which it is housed and in which the ball is properly guided.

Other objects will appear in the course of the following description.

My invention is illustrated in the accompanying drawing, wherein:—

Figure 1 is an elevation of an engine and a portion of the instrument board showing my device applied thereto;

Figure 2 is a front elevation of the ball 60 and air controlling valve;

Figure 3 is a longitudinal vertical section through the dial and air controlling valve;

Figure 4 is an elevation of the barrel 65 showing the ball and spring guiding means therein.

Referring to this drawing, 10 designates a barrel or inlet pipe of any desired diameter but which in actual practice will have 70 an internal diameter of approximately half an inch, the lower end of which is formed with a screw-threaded nipple 11 to which a pipe 12 as, for instance, copper tubing may be used, this copper tubing being carried 75 to the manifold 13 and engaged therewith so as to discharge air into the manifold.

The upper end of the barrel 10 is screw-threaded, as at 14, and extending upward from the barrel are a plurality of guides 15 80 of thin metal which may be formed integral with the tube or attached thereto in any suitable manner. Having engagement with the threads 14 is the cap 16 which constitutes a valve casing and which is formed with the 85 longitudinal bore 17 and at the lower end of said bore with the hemi-spherical seat 18 within which the ball valve 19 seats. Obviously the ball valve is of greater diameter than the bore 17 and inasmuch as the seat 90 18 and the ball are ground so as to have an air-tight fit, it follows that when the ball is held to its seat no air will pass through the bore 17.

The ball is held to its seat by means of 95 a coiled spring 20 which is smaller in diameter than the bore of the barrel 10 and seats at its lower end against a shoulder 21 formed at the lower end of the barrel. This spring bears upward on the ball and holds it to its seat but at every suction stroke of the engine the ball is drawn from its seat and air passes downward through the barrel 10 and through the copper pipe 12 into the manifold 13 and so to the cylinder which is 100 105 being charged.

Mounted upon the upper end of the head or cap 16 is a plate 22 having an aperture 23 to engage the screw-threaded end of the member 16. Pivotally mounted upon this plate is a cut-off valve 24 in the form of a blade pivoted upon a screw 25 which passes 110

into the plate 22, this screw being surrounded by a spring 26 which bears against the cut-off valve 24 and urges this valve tightly down against the face of the plate. When the valve is turned in one position it will entirely cut off the passage of air through the opening 23. When the valve is turned to entirely clear the opening 23, it is obvious that a full charge of air may pass downward through the valve casing but the valve may be turned to cut off any desired amount of air passing through the opening 23 so that the amount of air may be reduced or increased as desired.

15 Preferably the extremity of the valve is formed with a pointer operating over a scale 27 so that by shifting the valve in accordance with this scale any desired amount of air may be admitted. This plate 22 has 20 screw openings through which screws 28 may pass to hold the plate to the instrument board. Any other suitable support for this plate may be made. Preferably there will be a stop 29 which will limit the movement 25 of the valve to its closed position and one of the screw heads 28 may constitute another stop limiting the valve to a fully open position.

30 In order to control the pressure of the spring upon the valve 19, I have provided means for controlling the tension of the spring. This tension is controlled by relatively turning the valve 10 and the member 11 into or out of each other to a greater 35 or less degree and the adjustment of the member 11 in the barrel 10 may be accomplished by simply rotating the member 11 with reference to the barrel 10, and the member 11 is held in its rotated position 40 with reference to the barrel 10 by means of the jam nut 30.

It is particularly necessary that the spring should have free movement within the barrel 10 and that, therefore, this spring 20 45 should not bear in any way against the side walls of the barrel, and furthermore

absolutely necessary that the ball shall have free vertical movement and that it shall bear fully against its seat 18 when the valve is closed so as to absolutely prevent the entrance of air. When the valve is opened, however, by a compression of the spring due to suction of the engine, the air entering the bore 17 will pass freely around the spherical valve. 50 55

I have found in actual practice that this device operates very effectively upon motor vehicles inasmuch as by its use I greatly reduce the amount of gasoline or other fuel consumed per mile. This has been found by 60 actual test. Furthermore, I find that the introduction of air into the manifold at this point seems to increase the energy of the motor. While I have illustrated the barrel 10 as being disposed at or adjacent the 65 instrument board or projecting from the dial or plate 22, I do not wish to be limited to this position as it is obvious that this member 10 with its valve casing 16 and member 11 might be disposed anywhere in the 70 length of the pipe 12, either closely adjacent to the manifold 13 or closely adjacent to the plate 22.

I claim:—

The combination with the manifold of 75 an engine, of an air valve casing connected to the manifold, a valve therein opening upon suction within the manifold, a spring normally holding the valve closed, manually operable means for controlling the amount 80 of air passing through said valve including a plate having an inlet opening leading to the valve, a blade-like valve oscillatably mounted upon the plate, and a spring urging said blade-like valve against the plate, said 85 blade-like valve being formed at one end with a finger hold and at its opposite end with a pointer, the face of the plate being formed with a scale over which said pointer moves.

In testimony whereof I hereunto affix my 90 signature.

ELMER A. EKLUND.
